CLAIM

The ornamental design for a scouring article, as shown and described.

DESCRIPTION

FIG. 1 is a perspective view of a scouring article;

FIG. 2 is a top view thereof;

FIG. 3 is a bottom view thereof;

FIG. 4 is a front view thereof, the rear view being a mirror image of the front view; and,

FIG. 5 is a right side view thereof, the left side view being a mirror image of the right side view.

The surface shading illustrated in the drawings is provided merely to highlight the contour of design; it is not intended to be illustrative of texture or gloss. The cross hatching on the top of the scouring article is representative of the color blue and the solid on the bottom of the scouring article is representative of the color white.
